UNITED STATES PATENT OFFICE

2,479,033

GRAVITY TYPE OIL BURNER

Robert C. Veit, East Detroit, Mich.

Application October 22, 1946, Serial No. 704,955

3 Claims. (Cl. 158—91)

1

The present invention relates to improvements in oil burners, particularly of the type in which the oil is fed to the combustion chamber by gravity.

The object of the present invention is to provide an oil burner of the gravity feed type in which secondary air is introduced into the combustion chamber in such a manner that a more complete mixing thereof with the vaporized fuel and primary air is effected than with previously known burners of this type.

Another object of the invention is to introduce completely vaporized fuel and the secondary air into the combustion chamber in a manner that precludes the possibility of the collection of carbon in the chamber to interfere with proper combustion.

A further object of the invention is to provide for preheating the primary fuel vaporizing air and the fuel, and for distributing the vaporized fuel into the combustion chamber by a compact and easily fabricated structure.

Other objects and advantages of the invention will be apparent from the following description of a preferred form of the invention, reference being made to the accompanying drawings wherein:

Fig. 1 is a vertical cross-section view of a gravity feed type oil burner, the section being taken on line 1—1 of Fig. 2; and

Fig. 2 is a view taken on line 2—2 of Fig. 1.

Referring to the drawing, I have shown a burner adapted to burn a hydrocarbon fuel such as petroleum, oil or kerosene, and in general, it comprises a chamber 5 having a fuel vaporizing structure 6 located centrally thereof. The vaporizing structure is adapted to feed vaporized fuel into an annular combustion chamber or zone 7 where such fuel is mixed with secondary air and completely burned.

The chamber 5 is formed of a bowl-like member 10 having a substantially flat bottom wall 11 and a conical formation or cone 12 at the center thereof, the purpose of which will be more fully explained hereinafter. A shoulder 13 is formed about the bowl adjacent the top thereof for receiving a tubular cover 14. The cover 14 preferably has imperforate side walls, and the top thereof is closed except for an opening 15 for connecting the burner with a flue, not shown. The bowl 10 may be supported by a tubular member 17 received between circularly arranged lugs 18, or if desired, the bowl could be supported by laterally extending lugs 19.

The fuel vaporizing structure includes the cone

2

12 which has a fuel inlet opening 20 extending axially therethrough and which is adapted to supply fuel oil to the top of the formation. The oil is fed by gravity to the burner through a pipe 21 threaded into the bottom of the opening 20, and which leads from an oil reservoir, not shown. Two circular, concentrically arranged walls 23 and 24 are formed extending upwardly from the bottom wall 11 of the bowl, the base of the wall 23 being adjacent to the periphery of the base of the cone 12. A plurality of passages 25 are formed which extend radially from the base of the cone outwardly through the walls 23 and 24. The outer ends of the passages 25 terminate at the outer surface of wall 24. The passages are formed by the bottom wall 11 and semi-tubular wall portions 27. The passages 25 serve to conduct jets of vaporized fuel from the central portion of the bowl 10 outwardly to combustion zone 7. Any desirable number of passages 25 may be formed, and in the embodiment shown there are six such passages equally spaced from one another.

Portions of the bottom wall 11 intermediate the walls 23 and 24 and the passages 25 are open, as at 28, for forming air passages into the space between the walls 23 and 24. The upper edge of the wall 23 is undercut for forming a shoulder 30 thereabout and a vertical stack 31 is adapted to rest on the shoulder 30. The stack 31 is open at top and bottom and forms a passage for directing air downwardly to the conical formation 12.

The outer wall 24 has a circular shoulder 33 formed thereabout and a dome-like cover 34, open at the bottom and closed at its upper end by a wall 35, is adapted to rest on the shoulder 33. It will be observed that the cover 34 and stack 31 form a passage for air as indicated by the arrows 36 so that air may enter the openings 28 in the bottom of the bowl 10 and will rise vertically between the stack and cover and then descend down the stack and flow over the cone 12 and laterally through passages 25 to the combustion zone. Air entering the burner in this manner is referred to as primary air and it serves to assist in vaporizing the fuel.

In the combustion zone 7, intermediate the wall 24 and the outer vertical wall of the bowl 10, a plurality of secondary air inlets 38 are formed. The inlets 38 are formed by a member having a closed top wall 39 and the side walls are open at 40 so that air entering openings 41 in the bottom wall of the bowl flow upwardly and radially into the combustion zone 7. Preferably, there is a

secondary air inlet 38 disposed intermediate each of the outlets of the passages 25.

In operation, fuel is fed to the top of the cone 12 through the inlet 20 and the oil flows down the surface of the cone and through the passages 25 into the combustion zone 7. The fuel is then ignited by any suitable means, as by dropping a match therein, and the ensuing combustion causes air to be drawn upwardly through the secondary air inlets 38 and also primary air will be drawn through the air passage formed by the stack 31 and cover 34. This latter air will be heated as it passes upwardly between the cover and stack, as the cover will be heated by the combustion in the zone 7. Also, the cone 12 will be heated by conduction through the wall 11 of the bowl 10. By passing hot air over the fuel and also heating the surface over which the fuel is flowing, complete and rapid vaporization of the fuel will occur. Thus, very shortly after the ignition of the oil in the fuel chamber, only completely vaporized fuel is fed through the passages 25 into the combustion zone where it is thoroughly mixed with secondary air entering the inlets 38. The passages 25 are of such cross-sectional area that they produce a substantial jet effect for the vaporized fuel being fed to the combustion zone. The latter thereby creates turbulence in the combustion zone to thoroughly intermix the vaporized fuel with the secondary air. This causes complete combustion of the fuel without the formation of carbon, and a maximum heat is thereby obtained from the fuel. When mixing the secondary air in the manner described, formation of carbon is eliminated, that would tend to clog the burner and otherwise interfere with complete combustion.

It will be understood that the flow of fuel to the burner may be controlled by any suitable manner. For example, such control could include a valve that is adapted to be closed by a thermostatic element in the event the flame is accidentally extinguished.

My improved burner is particularly adapted for space heaters, cooking stoves or any other similar use in which a compact, inexpensive and soot free burner is desired. The structure lends itself to low cost production and yet the maximum heat will be yielded for the fuel.

Although I have described but one form of the invention, it will be understood that other forms may be employed, all falling within the scope of the claims which follow.

I claim:

1. An oil burner comprising, means forming a chamber having a substantially flat bottom wall; a conical formation at the central portion of the bottom wall, said formation having a fuel inlet opening at the top through which liquid fuel is fed to the conical surface of the formation; a vertical, open tubular stack immediately above said cone and axially aligned therewith; a dome-like cover in said chamber enclosing said stack and cone, and spaced from the sides and top of the stack for forming an air passage to the stack, said cover also being spaced from the sides of the pot for forming an annular combustion chamber, said bottom wall having air inlet openings in registration with the passage be-

tween the cover and stack; and means forming radially extending passages leading from adjacent the base of said conical formation into said combustion chamber, said last mentioned means comprising portions of said bottom wall and semi-tubular members over said portions.

2. An oil burner comprising, means forming a combustion chamber; a conical formation at the central portion of the bottom wall of said chamber, said formation having a fuel inlet opening at the top through which liquid fuel is fed to the conical surface of the formation; a vertical open tubular stack surrounding the base of said formation and extending above the top of said formation; a dome-like cover in said chamber enclosing said stack and cone, and spaced from the sides and top of the stack for forming an air passage to the stack, said cover also being spaced from the sides of the chamber for forming an annular combustion zone, said bottom wall having air inlet openings in registration with said combustion zone and having air inlet openings in registration with the passage between the stack and cover; and means forming radially extending passages leading from adjacent the base of said conical formation and extending through openings in the stack and cover into said combustion zone.

3. An oil burner comprising, means forming a combustion chamber comprising top, side and bottom walls; a conical formation at the central portion of the bottom wall of said chamber, said formation having a fuel feed opening at the top through which liquid fuel is fed to the conical surface of said formation; a vertical open tubular stack surrounding the base of said conical formation and extending vertically and above the top of said formation; a dome-like cover in said chamber enclosing said stack and conical formation, and spaced from the side and top walls of the stack for forming an air passage to the stack, said cover also being spaced from the side walls of the chamber for forming an annular combustion zone, said bottom wall having air inlet openings therethrough into said combustion zone and having air inlet openings in registration with the passage between the stack and cover; means forming radially extending passages leading from adjacent the base of said conical formation and extending through openings in the stack and cover into said combustion zone, and the top wall of said chamber having an exhaust opening in alignment with the top of the domed cover, so that products of combustion will be drawn over the top of the cover when they are exhausted from combustion chamber.
